UNITED STATES PATENT OFFICE.

VINCENT WESTERVELT, OF BLOOMINGDALE, NEW JERSEY.

CURTAIN-BRACKET.

1,313,768.

Specification of Letters Patent.

Patented Aug. 19, 1919.

Application filed November 21, 1918. Serial No. 263,539.

To all whom it may concern:

Be it known that I, VINCENT WESTERVELT, a citizen of the United States, residing at Bloomingdale, in the county of Passaic and State of New Jersey, have invented new and useful Improvements in Curtain-Brackets, of which the following is a specification.

This invention relates to improvements in shade and curtain brackets and aims to provide means for adjustably securing curtain and shade brackets in position upon a window frame.

An object of the present invention is to provide means whereby the shade bracket may be adjustably and removably secured upon a suitable base plate, (adapted to be secured upon a window frame,) in a manner to adjustably and removably secure a curtain bracket upon said plate, thereby permitting of a quick and convenient adjustment of one or both brackets.

Another object is to provide means for positively holding the brackets against accidental movement, which consists in providing grooves having inclined walls for the reception of securing nuts, which latter are prevented from turning and wedged into position by said walls, these walls also providing a groove upon the opposite or other face of the base plate to receive an arm carried by the curtain bracket.

Other objects and advantages of the invention will appear as the following description is read in connection with the accompanying drawings.

In the drawings:—

Figure 1 is a face view of a combined shade and curtain support constructed in accordance with the present invention;

Fig. 2 is an end view thereof;

Fig. 3 is a transverse sectional view;

Fig. 4 is detail perspective view of the base plate;

Fig. 5 is a similar view of the curtain bracket; and

Fig. 6 is a like view of one of the securing ends.

Referring in detail to the drawings, where in like characters of reference denote corresponding parts, the base plate of the support is shown at 10. This plate is preferably stamped from sheet metal and is provided with longitudinally disposed spaced parallel grooves 11, which are surrounded by

inclined flanges 12. These flanges provide longitudinally disposed seats 13 upon the rear face of the base plate for the reception of nuts 14, the latter being engageable with screws or bolts 15 passing through the apertured base 16 of a shade bracket 17. By having the flanges 12 inclined as shown, the seats 13 are provided with inclined walls, for engagement with the inclined edges 18 of the nuts 14. This prevents turning of the nuts during the adjustment of the bracket 17 in position and also acts to tightly wedge the nuts within the seats, thereby preventing them from becoming accidentally loosened and securely holding the brackets in position.

The opposed flanges 12 of the grooves 11, provide guides upon the outer face of the base plate which is offset from the base of the plate 10, so that a relatively shallow groove is formed. This groove is adapted to receive a right angularly disposed arm 20, carried by the curtain bracket 21. This bracket is preferably formed of a base of L-shaped metal, one arm of which provides the arm 20 and the offset arm is bent to form a seat 22 for the reception of the curtain pole. The arm 20 is placed within the groove 19 and held in adjusted position therein through the medium of the shade bracket 17, the base 16 of which extends transversely across the groove in contact with the arm 20.

This provides for the quick and convenient adjustment of either one or both brackets, as by loosening the screws 15 the bracket 17 may be moved longitudinally of the base plate, of the bracket 21 similarly moved.

The invention is susceptible of various changes in its form, proportions and minor details of construction and the right is reserved to herein make such changes.

Having described the invention, what is claimed is:—

1. A shade and curtain support comprising a base plate having longitudinally disposed parallel grooves, outwardly extending inclined flanges surrounding said grooves to define longitudinal adjusting seats, a shade bracket contacting with the outer edges of the inclined flanges, threaded fastening devices engageable with said bracket, nuts threaded upon said device, inclined edges for said nuts, said edges being adapted for contact with the inclined flanges, whereby the

- nuts are wedged into the adjusting seats, a curtain bracket and means whereby the shade bracket will hold the curtain bracket upon the base plate.
- 5 2. A shade and curtain support comprising a base plate having longitudinally disposed parallel spaced grooves, outwardly inclined flanges surrounding said grooves and defining a longitudinally disposed adjusting seat between the opposed flanges of opposite

grooves, a curtain bracket, a right angularly disposed arm carried by said bracket and adapted to be received in the longitudinally disposed adjusting seat, a shade bracket positioned transversely across said seat in contact with the right angular arm of the curtain bracket and means for removably securing the shade bracket to the support. 15

In testimony whereof I affix my signature.
VINCENT WESTERVELT.
